The ornamental design for a door panel for animal pen, as shown and described.

DESCRIPTION

FIG. 1 is a top rear perspective view of a door panel for animal pen according to the design;

FIG. 2 is a bottom rear perspective view of the door panel of FIG. 1;

FIG. 3 is a top front perspective view of the door panel of FIG. 1;

FIG. 4 is a bottom front perspective view of the door panel of FIG. 1;

FIG. 5 is a rear elevation view of the door panel of FIG. 1;

FIG. 6 is a front elevation view of the door panel of FIG. 1;

FIG. 7 is a first side elevation view of the door panel of FIG. 1;

FIG. 8 is a second side elevation view of the door panel of FIG. 1;

FIG. 9 is a top plan view of the door panel of FIG. 1; and, FIG. 10 is a bottom plan view of the door panel of FIG. 1. The broken lines in the drawings depict portions of the door panel for animal pen that form no part of the claimed design.
